UNITED STATES PATENT OFFICE.

HERMANN LEROY BEAVER, OF PHILADELPHIA, PENNSYLVANIA.

STEEL PEB.

Application filed April 15, 1922. Serial No. 552,977.

To all whom it may concern:

Be it known that I, HERMANN LEROY BEAVER, a citizen of the United States, residing at Philadelphia, in the county of Philadelphia, State of Pennsylvania, have invented certain new and useful Improvements in Steel Pebs, of which the following is a description, reference being had to the accompanying drawing and to the figures 10 of reference marked thereon.

This invention relates to polishing material for polishing or burnishing metal articles, including plated ware and manufactured parts.

16 Heretofore, in polishing or burnishing metal articles, it has been customary to place the articles in a tumbling barrel together with the polishing material generally consisting of rejected polished steel balls and 20 special shapes, such as oats, spickets or other specially made pointed steel forms. These special shapes were found indispensable for the reason that the balls alone while ideal for burnishing smooth surfaces, were never able 25 to polish the crevices, corners, irregularities or small indentations in the surfaces to be polished. But the one great objection to the special shapes lay in their inordinate cost since they were either die or machine made.

30 The main object of the present invention resides in providing an improved polishing material which is not only economical to manufacture, but which combines the polishing qualities of both the steel balls and the 35 existent specially made polishing shapes having the projections.

Another object of this invention resides 40 in providing a polishing material which will most effectively polish the complete surface of the article, due to the fact that each polishing unit possesses an individual and distinctive shape, generally including in its contour, a rounded surface together with one 45 or more projections, so that the units because of the great diversity of shapes, are better suited to project into the variantly contoured superficial angularities and irregularities of the articles to be polished.

These and other objects will be apparent 50 from a perusal of the following specification when taken with the accompanying drawing, wherein—

The figure discloses a few of typical shapes of the polished steel units.

55 In its broad aspect, the invention resides in the novel product and in the process of

producing a finished metal polishing or burnishing material, comprising polished metallic units, each of which has its distinct, substantially irregular form or shape, resembling pebbles in this respect, with their individual irregularities and variant contours.

These steel pebble-like shapes include not only approximately round metallic polishing units, but also units which comprehend a rounded polished surface and one or more polished projections or jutting surfaces of divers shapes and sizes, which are manifestly most effective on polishing those parts 70 which cannot be burnished by the substantially round polishing units.

As a novel process of making my improved polishing form or units, I atomize a stream of molten iron by means of a column of steam or the like. The steam contacting with the molten metal explodes it violently, disrupting the metal into small particles of variant sizes which, falling through the air, assume somewhat spherical 80 shapes of varying irregularities and contours. In particular, the disruptive force of the steam tends to produce on these substantially rounded forms, small fins, projections or complex jutting surfaces which persist 85 in the finished unit. In traversing the air, these forms become superficially chilled and take their permanent set before falling into a body of water where they are chilled to intense hardness.

These chilled metal blanks or forms are now treated to remove the coating of rust and scales resulting from the rapid oxidation during the foregoing stage in their formation. To this end, the blanks are placed 90 in preferably cast iron tumbling barrels, to which is added a predetermined quantity of abrasive material, such as Vienna lime and the mass is then covered with water to a depth of one or two inches. The barrel is 100 then operated for a considerable period during which time the action of the abrasive cleans and polishes the surface of the blanks and smooths off all rough edges. The blanks are then washed, preferably in boiling water 105 to remove all trace of the polishing material and are then dried desirably in wood flour in a riddle. The blanks are now placed in wooden tumbling barrels with the necessary quantity of leather clippings or the like, 110 and operated until the blanks are highly buffed. This operation completes the treat-

ment of the blanks, except for a slight inspection wherein certain ill-formed blanks, such as those blanks which stick together in irregular masses or strings, are picked out.

5 As a result of the foregoing process, each blank is given a high polish. The surface of each blank is absolutely glass-hard and cannot be touched with a fine Swiss file. With respect to shape, these blanks differ 10 from ordinary rejected bearing balls which have heretofore been used for burnishing purposes, in that bearing balls are absolutely round and are drawn after hardening to toughen them to resist load shocks, there- 15 by destroying at least partially their efficiency for proper burnishing work. In general, these finished blanks or metallic forms tend to assume somewhat of a round shape, but the majority of them include irregular 20 curved surfaces of varying radii. The various shapes illustrated in the drawing are fair examples of the various outlines and divers polished forms corresponding to the finished blanks. It will be noted that some 25 of the distinctive forms are the pear-shaped taper form, which has the appearance of a combination of a round ball and a steel oat. In other words, the incorporation of a curved ball surface and a drawn point. Some are 30 spheroidal in form, and few, if any of them, are substantially round, even though they have a rounded appearance.

The polishing action of these metallic polished pebbles or finished blanks is comparable to the burnished tool in the hands of a workman in that it is used in a large mass, and the weight of these particles pressing down on the material to be burnished, forces these particles to travel over the 35 surface of the articles in the barrel, thereby causing the burnished finish. The polishing units or pebbles, because of their multiplicity of shapes or forms have a greater break-up and a more eccentric wave to effect 40 the burnish or polish on a given article than could be obtained than by using perfectly round balls or a mixture of perfectly round balls or spickets, which are merely snibs of wire, generally $3/32$ " in diameter and $3/8$ " 45 long, or steel oats which are double pointed steel shapes resembling an oat grain, or cones which are double pointed with an intervening flange, for the reason that these pebbles entirely eliminate the necessity for 50 such added auxiliary polishing elements,

such as the oats, cones and spickets. This is due to the fact that each of my polishing blanks, or at least, a great majority of them, incorporate both the rounded surface and a 60 projecting surface corresponding to that of one of these auxiliary polishing elements, which latter are shaped to find their way into crevices, where a true ball, by reason of its curved surface, cannot go. Experience has shown that the varying shapes and 65 sizes of projections on the finished blanks will satisfactorily and successfully burnish down into angles as small as $1/64$ ".

It is evident that a polishing material such as has been just described possesses 70 marked advantages over any material heretofore used, first, for the reason that the various unsymmetrical shapes and odd sizes incorporating both the rounded surface and the various shaped projections, also of different sizes, permit the units to shift about and make polishing contact with indentations, superficial irregularities and angular surfaces on the article to be polished, and 75 secondly, if not mainly, for the reason that the above-described polishing material can be made much more economically than the existing polishing material now used, due to the fact that the latter includes the specially made shapes which are extremely expensive.

It is obvious that minor changes in the details of construction and the arrangement of the parts may be made without departing from the spirit of the invention as set forth 90 in the appended claims.

Having thus described the invention, what I claim as new and desire to secure by Letters Patent, is—

1. A metal polishing material comprising 95 heteromorphic, asymmetrical polished metallic units, a portion of which have projections adapted to make polishing contact with the angular surfaces of the metal part to be polished.

2. A metal polishing material comprising a plurality of polished metallic units, each of which is substantially pebble-shaped whereby the various irregular shapes and contours of the units will make polishing contact with the angular surfaces of the parts to be polished.

In testimony whereof, I affix my signature.

HERMANN LEROY BEAVER.
